United States Patent Office

Des. 214,184
Patented May 20, 1969

214,184

WARMING STAND

William J. Rackocy, Clifton, N.J., assignor to Ronson Corporation, Woodbridge, N.J., a corporation of New Jersey

Filed May 15, 1968, Ser. No. 11,950

Term of patent 14 years

Int. Cl. D7—02, 04

U.S. Cl. D44—10

FIG. 1 is a front perspective view of a warming stand showing my new design.

FIG. 2 is a top view thereof.

FIG. 3 is a front view thereof.

FIG. 4 is a right-side view thereof.

FIG. 5 is a bottom view thereof.

A support strut is omitted in FIG. 3 for convenience of illustration only. In FIGS. 2 and 3, the broken line showing of a gas fired burner is for illustrative purposes only.

I claim:

The ornamental design for a warming stand, substantially as shown and described.
